DYEING MACHINE

Frank Roselene, Paterson, N. J.

Application March 2, 1946, Serial No. 651,656

4 Claims. (Cl. 242—55)

1

The present invention relates to improvements in equipment used for the winding and unwinding of materials supplied in roll form, such as cloth, paper, and the like. More particularly, though not exclusively, the invention concerns a driving mechanism to be used in connection with a dye jig for coloring textile fabrics.

One of the prerequisites for obtaining a uniform coloring effect in a dye jig is that the material pass through the vat containing the liquid at a substantially uniform speed. Moreover, when the material is unwound from one roller and wound upon another, it is obviously desirable that both rollers be driven at substantially the same circumferential velocity. This is complicated by the fact that the diameter of the leading roller increases as that of the trail-roller decreases, and recourse has been had in the past to driving only the former by means of gears alternatively connectable with either shaft. Variable speed devices and adjustable braking mechanisms have been proposed to regulate the speed of the fabric, but these more or less cumbersome contrivances are only partial solutions of the problem. A further difficulty exists due to the fact that the transmission of motion between the two rollers places an unwanted and sometimes detrimental strain upon the material to be processed, particularly where a considerable braking movement is applied to the trailing member. Unrestricted motion of the latter, on the other hand, may give rise to equally harmful oscillations caused by the resiliency of the fabric.

One object of the present invention is to provide a simple and effective driving mechanism that eliminates the above shortcomings by comprising a pair of rollers which are positive-driven from a common power source.

Another object of this invention is to provide a pair of driven rollers rotating in synchronism at a constant and conveniently adjustable circumferential speed.

A further object of the invention is to eliminate, in an apparatus of the kind described, the danger of overstressing the fabric.

A still further object is the elimination of excessive braking action.

Reference is now made to the accompanying drawing showing a preferred embodiment of the invention.

Fig. 1 is an elevational cross section of a mechanism according to the invention, associated with a dye jig;

Fig. 2 is a fragmentary horizontal section on a larger scale, taken on line 2—2 of Fig 1;

2

Fig. 3 is a section along line 3—3 of Fig. 1.

According to the invention, there is provided a drive shaft 10 bearing the main roller 11 which is flanked by two auxiliary rollers 12 and 13. The shaft 10, as well as two guiding rollers 14 and 15, are journaled in bearings unitary with or otherwise secured to the two halves of the frame 16 of the dye jig, the two halves being connected by tie-rods 17 which are surrounded by spacers 18 and engaged by end nuts 19. A bottom roller 20 is journaled in the vat 21 containing the liquid; the vat is provided with a drain 21 and may be suspended between rods 22 which are supported by lugs 23; these lugs are suitably secured to frame 16. Additional support for the vat 21 may be provided in the form of blocks 24, disposed at spaced intervals along its bottom.

The auxiliary rollers 12 and 13, as is best shown in Fig. 2, are journaled in bearing blocks 25, two such blocks being provided for each roller at the two ends thereof. The blocks are slideable in horizontal channels formed by extensions of the frame 16, and springs 26 act upon these blocks tending to press the auxiliary rollers 12, 13 against the main roller 11. The tension of the springs 26 may be regulated by means of adjusting screws 27.

Mounted upon each half of the frame 16 is a standard 28 comprising two substantially vertical channels which accommodate the slideable bearing blocks 29. Two rollers, 30 and 31, are lodged in respective pairs of opposite bearing blocks 29 and constitute the leading and trailing members of the system. In the drawing, roller 31 has been shown fully loaded; if this is assumed to be at the beginning of an operating cycle, the material is to be unwound from roller 31 and wound upon roller 30 which thus acts as the leading member. Power is derived from a motor (not shown) by means of a pulley 32 as fastened to the drive shaft 10.

The manner of operation of the mechanism will now be apparent to those skilled in the art. The material taken from roller 31 is initially inserted between the main roller 11 and auxiliary roller 13, conducted past the guiding roller 15, around bottom roller 20, and past guiding roller 14, inserted between rollers 11 and 12, and finally wound around the leading roller 30. The pulley 32 is driven by the motor at a suitable, preferably constant, speed which the roller 11 communicates by friction to the rollers 12 and 13. The leading member 30, sliding freely in a vertical direction, is forced by gravity to ride

on the roller 12 and thereby to rotate at a peripheral speed substantially equal to that of the three rollers 11, 12, and 13. As the diameter of this member increases, its R. P. M. will drop, but the peripheral speed caused by frictional contact with the roller 12 will not change. At the same time, the growing radius will gradually raise the shaft of roller 30 until the latter finally reaches a position corresponding to the initial position of roller 31, as shown in dot-dash line 10 in Figs. 1 and 3.

Meanwhile, in identical manner, the trailing member 31 is forced to follow the movement of roller 13 and thus to rotate at a peripheral speed equalling that of the other rotating members. 15 As the diameter decreases, the roller 31 gradually descends and finally comes to rest in a position likewise indicated by a dot-dash line in Fig. 1. The material may now be subjected to further treatment in the jig by simply reversing the direction of rotation of pulley 32.

It may be safely assumed that the weight of even the unloaded leading roller will provide sufficient pressure to prevent any appreciable slip-page thereof, particularly since no additional pull 25 need be exerted by this member, transportation of the fabric being assured by the cooperation of roller 11 with rollers 12 and 13. On the other hand, this vertical pressure may be increased by the application of extra weights. Again, horizontal spring pressure may be optionally applied only to auxiliary member 12, or 13, or neither of them, without departing from the scope of the invention which is based on the idea of driving one or more rollers at substantially the peripheral speed 30 of a central driving member. This speed corresponds to the rate of travel of the material being treated, whereby such rate of travel may be conveniently adjusted to any desired value, constant or otherwise.

I claim:

1. A driving mechanism for use with a dye jig, comprising a support, a cylindrical roller horizontally journalled in said support, a pair of auxiliary rollers flanking and adjacent said cylindrical roller and journalled in bearing members 45 slidable in horizontal direction, said three rollers having substantially equal diameter, a plurality of springs arranged for pressing said bearing members toward said central roller, a pair of rollers journalled in vertically slidable bearing members and respectively arranged for normally riding on said auxiliary rollers, the material to be processed being wound on one or both of said 50 vertically slidable rollers, and driving means connected to said cylindrical roller.

2. A dyeing machine of the character described comprising a mounting frame, a central roller journalled in said frame; a pair of idling rollers slidably journalled one on each side of said central roller; a second pair of rollers slidably journalled in said frame and riding upon said pair of idling rollers, and a plurality of guide rollers by which a flexible web of material may be wound from one of said second pair of rollers riding on 10 said idling rollers onto the other.

3. A dyeing machine of the character described comprising a mounting frame; a central and driven roller fixedly journalled in said mounting frame; a pair of idling rollers journalled on either side of said central roller in frictional contact with same, said idling rollers having slideable bearings under spring tension forcing same against said centrally driven roller, a second pair of rollers having slideable bearings, 15 said bearings being slideable in a vertical sense, and said rollers being located parallel to and on top of said pair of idling rollers, and said rollers being furthermore in frictional contact with said idling rollers.

4. A dyeing machine of the character described comprising a mounting frame; a driven roller centrally journalled in said mounting frame; a pair of idling rollers journalled in bearings horizontally slideable in said mounting frame, said bearings being spring loaded whereby same are pressed against said central roller in a frictional connection; adjustable means for varying said spring tension on said idling rollers, a pair of cylinders containing a web of flexible material, said cylinders having bearings vertically slideable in said mounting frame, one of said cylinders being located directly above each of said idling rollers and parallel to same, and a plurality of guide rollers whereby said flexible web of material may be wound with constant peripheral speed from one roller onto the other, by means of a frictional drive through said idling rollers.
